Oscar L. Owen ATTORNEY.

UNITED STATES PATENT OFFICE.

RICHARD WATSON McVEY, OF ADAMS, MASSACHUSETTS, ASSIGNOR TO WHITIN MACHINE WORKS, OF WHITINSVILLE, MASSACHUSETTS, A CORPORATION OF MASSACHUSETTS.

BUNCH-BUILDER MECHANISM.

Application filed May 26, 1923. Serial No. 641,602.

To all whom it may concern:

Be it known that I, RICHARD WATSON McVEY, a citizen of the United States, residing at Adams, in the county of Berkshire and Commonwealth of Massachusetts, have invented a new and useful Improvement in Bunch-Builder Mechanisms, of which the following is a specification.

This invention relates to spinning machines of that type constructed to wind on the yarn bobbin first a preliminary winding or "bunch" then a main winding, and the principal object of the invention is to provide a mechanism for controlling the traverse of the ring rail for laying the preliminary winding and automatic means of simple and inexpensive construction whereby the preliminary winding mechanism is rendered inoperative after the "bunch" has been formed.

Another object of this invention is to provide adjustable means whereby the size and position of the bunch may be varied.

With these objects in view, the invention comprises certain novel constructions, combinations and arrangements of parts as will be hereinafter specified and claimed.

In the drawings:

Figure 1 is a front elevation of a sufficient portion of a spinning machine embodying the invention to make clear its construction and manner of operation.

Figure 2 is an enlarged section on the line 2—2 of Figure 1;

Figure 3 is a detached detail showing the locking latch in its inoperative position;

Figure 4 is an end elevation of Figure 3;

Figure 5 is an enlarged section on line 5—5 of Figure 3;

Figure 6 is an enlarged section of the builder cam on diametrical line 6—6 in Figure 2;

Figure 7 is an enlarged front elevation of the knock-off lug cam;

Figure 8 is an end elevation of the same; and

Figure 9 shows an alternative construction of knock-off means of the locking latch.

The invention is herein illustrated as applied to a ring spinning machine, wherein the head end 1 is fastened to bolster rails 2 the top of which supports a series of spindles provided with whorls 3 for rotating a series of yarn bobbins 4 mounted on the spindles. A lifter rail 5 has a series of rings 6 provided with the usual travelers, and is supported by the lifter rod 7, the lower end 8 of which rests upon a roll 9 mounted on the cross arm lever 10 pivoted at 11 upon the hanger 12 extending from the bottom of the bolster rail 2. The lever 10 is counterbalanced by a weight (not shown) whereby the upward traverse of the ring rail is effected. Extending upward from the lever 10 is a segment arm 13 to which is connected one end of a chain 14 which passes over the sheave pulley 15 and is then connected to the filling winding lever 16 working in conjunction with the builder lever 17 of usual construction pivoted at 18 on a stud fixed to the head end 1. While only a single lever 10 and lifter rod 7 are shown, it is to be understood that any suitable number of these may be used and may be connected, as usual, to move in unison to cause the ring rail 5 to move up and down under the control of the builder motion as is common and well understood in ring spinning machines.

The winding lever 16 to which the builder motion chain 14 is attached derives its motion from the rack 19 through action of the roll 20 fastened to the rack and coacting with the upper surface of the winding lever 16. Motion is imparted to the rack by the worm 21 fixed to the rotary shaft 22 held in suitable bearings on the builder lever 17. An intermittent motion is imparted to the shaft 22 by the ratchet 23 fixed thereon acting in conjunction with the pawl 24 carried on the arm 25 which is actuated by the rod 26 as the builder lever 17 is raised and lowered.

Mounted for rotative movement in the head end 1 is the cam shaft 27 which may be connected from any suitable source of

power as by the gear 28, Figure 1. A builder motion cam 29 of usual construction is fastened to the inner end of shaft 27. The rotation of the cam acting on follow 5 roll 30 revolvable on a stud fixed to the builder lever 17, causes the latter to swing up and down on its pivot 18 and through the connections between the builder lever and the ring rail the traverse of yarn be- 10 ing wound on the bobbin is effected.

The construction above described is common to spinning machines as now in use and as it is well understood by those skilled in the art, further explanation is deemed un- 15 necessary.

To suit particular requirements as to speed in the laying of the yarn onto the bobbins the cam 29 may have one or more cam points each of which causes an upward 20 and downward movement of the ring rail. The better to illustrate my invention I make use of a four point cam as shown. On the web or arm of one or more points of the cam 29, a cam shaped lug 31 is adjustably 25 mounted by suitable means such as bolt 38 and clamping plate 40.

Preferably I use two lug cams diametri- 30 cally opposite each other as shown in Figure 2. The number of lug cams and their dis- 35 tance apart determines the amount of yarn wound in the bunch on the bobbin. As the yarn forming the bunch is classed as waste in the process of weaving it is economy on the part of weavers to have the bunch 35 as small as is possible to perform its function with the feeler mechanism of weft replenishing looms.

Instead of mounting the lug cams on the builder motion cam 29 as above described, 40 an alternative construction (see Figure 9) may be had by using an independent cam 39 fixed to shaft 27, rotating in unison with cam 29, and operating in conjunction with the knock-off roll 37 to release the locking 45 member 32.

In order to effect the winding of the yarn in the form of a bunch at the lower part of the bobbin I retard the traverse of the ring rail by means of a locking latch 32 50 abutting against the builder lever 17. The latch is pivoted on a stud 33 fixed in bracket 34 in stationary relation to the framing of the machine; the latch being provided with an abutment member 35 adjustably mounted 55 on the lower part of the latch. About midway of the latch a stud 36 is fixed on which a revolvable knock-off roll 37 is held in the plane of rotation of the lug cam.

In operation the operative, after starting 60 the machine, depresses the ring rail by means of foot pressure applied to the end of lever 10, thus positioning the ring rail for the beginning of the bottom traverse of the 65 yarn. This action also depresses the builder lever to its lowest position acted thereon by

the cam 29. The operative then manually swings the latch 32 so that the member 35 rests on top of the lever 17 preventing it from moving upwardly, thus rendering the ring rail stationary and causing the yarn 70 to wind in a bunch; meanwhile the rotary motion of the cam 29 gradually brings the lug cam 31 into contact with knock-off roll 37, the shape of the lug cam being such that the locking action of the latch is removed 75 from the builder lever and in consequence the builder lever resumes its upward and downward motion without restriction thus permitting the main winding of the yarn on the bobbin in the regular manner. The 80 latch after being pushed from contact with the builder lever swings to such a position as to be just out of the path of motion of the builder lever. To prevent the latch from swinging into contact with the builder lever, 85 except when desired, means are provided to act as a brake to stop any swinging motion that might occur from vibrations of the machine, preferably I use a compression spring 41, one end held in a socket in the 90 upper part of latch and the other pressed against the surface of fixed bracket 34.

What I claim is:

1. In a machine of the character de- 95 scribed, the combination of a series of spin- 100 dles for supporting and rotating yarn bobbins, yarn guiding means, a builder lever, a rotary cam for operating said lever, a manually operated locking member pivoted to a stationary part of the machine and 105 adapted to abut against the builder lever to retard its movements, one or more lug 110 cams adjustably mounted on the web or arms of the rotary cam, a knock-off mem- 115 ber in a fixed relation to the locking member and an abutting member adjustably mount- 120 ed on the locking member.

2. In a machine of the character de- 110 scribed, the combination of a series of spin- 115 dles for supporting and rotating yarn bobbins, yarn guiding means, a builder lever, a rotary cam for operating said lever, a manually operated locking member pivoted to a stationary part of the machine adapted 120 to abut against the builder lever to retard 125 its movements, means to maintain the lock- 130 ing member in an inoperative relation with the builder lever, one or more lug cams adjustably mounted on the web or arms of the rotary cam, a knock-off member in a stationary relation to the locking member and an abutting member adjustably mounted on the locking member.

3. In a machine of the character de- 125 scribed, the combination of a series of spin- 130 dles for supporting and rotating yarn bobbins, yarn guiding means, a builder lever, a rotary cam for operating said lever, one or more cam lugs adjustably mounted on the web or arms of said cam, a manually oper- 130

ated locking member pivoted to a stationary part of the machine adapted to abut against the builder lever to retard its movements, a compression spring located between the locking member and its support whereby the locking member is maintained in an inoperative relation with the builder lever, a

knock-off member in a stationary relation to the locking member and an abutting member adjustably mounted on the locking member. ¹⁰

In testimony whereof, I have signed this specification.

RICHARD WATSON MoVEY.
